Filed Apr. 1, 1974, Ser. No. 457,015

Term of patent 14 years

Int. Cl. D3—01

U.S. Cl. D87—8

FIG. 1 is a top perspective view of a key retainer showing my new design;

FIG. 2 is a top plan view thereof;

FIG. 3 is a bottom plan view;

FIG. 4 is a side view taken from the left of FIG. 2, the other side being a mirror image thereof;

FIG. 5 is a front elevational view;

FIG. 6 is a rear elevational view;

FIG. 7 is a fragmentary perspective view thereof with the retainer loop in an open position;

FIG. 8 is a second embodiment of the design of FIG. 1, the design being the same except for the peripheral contour;

FIG. 9 is a third embodiment of the design of FIG. 1, the design being the same except for the peripheral contour.

The undisclosed right side is a mirror image of the left side shown in FIG. 4.

The embodiments in FIGS. 8 and 9 are identical with the embodiment in FIGS. 1—7 except for the peripheral contour of the base in plan view.

I claim:

The ornamental design for a key retainer, substantially as shown and described.
